FRERES SOCIETE ANONYME, OF WINTERTHUR, SWITZERLAND

REFRIGERATING MACHINE

Application filed August 24, 1929, Serial No. 388,132, and in Switzerland October 18, 1928.

This invention relates to refrigerating machines more particularly of the kind in which the refrigerating medium is returned from the evaporator to the condenser by means of a rotary compressor.

5 Oil is used in the rotary compressor not only to lubricate the moving parts but also to seal the clearances between such moving parts, and thus to prevent the escape of the refrigerating medium and the consequent inefficiency of the machine. Comparatively 10 large quantities of oil are therefore circulated and, as some of the oil gets into the high pressure chamber of the compressor, the compressed refrigerating medium or gas is passed 15 through an oil separator before reaching the condenser. It is difficult however to effect perfect separation of the oil owing partly to the nature of some of the refrigerating media used and partly to the fact that the oil is to 20 some extent atomized in the slot-like clearances of the compressor. Further, in the case of machines which, owing to the nature of the refrigerating medium, have to work 25 with a high degree of superheat, as is the case in ammonia machines, the resulting high temperatures cause a partial evaporation of the oil. This evaporated oil can be condensed by cooling but an oil mist is likely to be 30 formed which it is difficult to eliminate from the gas.

The oil which is not separated out will thus pass through the condenser with the gas to the evaporator and will accumulate there, 35 particularly in the case of superheating machines in which only dry gas is drawn from the evaporator. This accumulation of oil in the evaporator causes a reduction in the efficiency of the evaporator by "wetting" the inner walls and thus reducing its heat conductivity and also by decreasing the effective working area of the evaporator. In addition there will be a reduction in the quantity of oil available for lubricating and sealing the compressor and as a result the compressor will 40 not function correctly.

The object of the present invention is to provide a return path to the compressor for oil passing with the refrigerating medium 45 through the oil separator into the condenser.

According to this invention an oil collector in which the oil sinks to the bottom owing to its weight is provided, together with a discharge pipe for connecting the collector directly to the suction chamber of the compressor, the arrangement being such that the discharge pipe of the oil collector is exposed to a lower pressure than the main discharge pipe of the evaporator. Conveniently the difference in pressure between the pipes is obtained by connecting the evaporator to the compressor through a loaded valve preferably of the adjustable non-return type.

When a multi-bladed rotary compressor with a crescent-shaped main suction chamber is provided, the discharge pipe of the oil collector may be connected to a subsidiary suction chamber separated from the main suction chamber by at least one blade pitch. An additional evaporator may be arranged in the collector discharge pipe preferably in such a way that liquid flow therethrough is in a downward direction.

The oil collector may be connected to the outlet side of the evaporator with or without a regulating valve in the collector discharge pipe, or may be arranged on the inlet side of and below the evaporator.

The following is a description by way of example of several arrangements of refrigerating machine constructed in accordance with the invention with reference to the accompanying drawings, in which

Figure 1 shows a sectional elevation of the rotary compressor, the other parts of the refrigerating machine being shown diagrammatically.

Figure 2 is a sectional end elevation of the compressor on the line II—II of Figure 1,

Figure 3 is a similar view to Figure 1 of a modified arrangement of refrigerating machine, and

Figures 4 and 5 show diagrammatically alternative arrangements of the oil collector forming the present invention.

Referring to Figure 1, a rotary compressor 1 is connected on the outlet side by a pipe 5 to a condenser 2 the discharge side of which is in turn connected through a pipe 6 to an expansion valve 3. The expansion valve 3 is 100

connected by a pipe 7 to an evaporator 4, the discharge pipe 8 of which is connected to the inlet side of the compressor 1. A closed circuit is thus formed through which the refrigerating medium circulates in the direction indicated by the arrows. An oil separator 9 is interposed in the pipe 5 so as to collect oil carried away by the refrigerating medium in the compressor and deliver it through a pipe 10 back to the compressor the direction of oil circulation being indicated by the dotted arrows. The rotary compressor itself, (Figures 1 and 2) comprises a working chamber 14 in which is mounted on a driving shaft 11 a multi-bladed rotor 12 having blades 13 which rotate in the direction indicated by the arrow. The working chamber 14 is bounded at the circumference by an eccentrically bored liner 16 and at the sides by two discs 17 in which are mounted ball bearings 18 for supporting the shaft 11, an outer cover 15 being provided at each end of the casing.

Between the covers 15 and the discs 17 are oil pressure chambers 19 and 20 which are connected by the oil pipe 10 to the oil separator 9 (Figure 1) and to each other by the channels 21, 22 and 23. During the working of the compressor the oil circulates from the chambers 19 and 20 through the clearances between the various working parts of the compressor which it lubricates and seals into the working chamber 14, and from thence is carried as previously stated with the refrigerating medium into the oil separator from which, of course, it returns to the compressor by the pipe 10. The cover 15 through which the end of the shaft 11 passes is provided with a disc 24 pressed by a spring 25 against a machined face of the cover which thus forms a tight joint for closing the oil pressure chamber 20.

As it is impossible entirely to separate out all the oil from the refrigerating medium in the separator 9, some of this oil passes out from the separator through the pipe 5 to the condenser 2, pipe 6, throttling member 3, pipe 7, and through the evaporator 4. In order to prevent oil accumulating in the evaporator an oil collecting chamber 26, hereinafter referred to as the oil collector, is provided in the main discharge pipe 8 of the evaporator in which the oil sinks to the bottom on account of its weight. This oil collector is connected by a pipe 27, which is separate from the main discharge pipe 8 of the evaporator, to the suction chamber 28 of the compressor 1.

In order that the oil shall be withdrawn from the collector 26 to the compressor, it is necessary that the pipe 27 should be exposed to a pressure which is less than that of the pipe 8. Accordingly, in the arrangement shown in Figure 1 a spring biased valve 29 is provided in the main discharge pipe of the evaporator. This valve 29 causes a fall in

pressure between the suction chamber 28 and the pipe 8 and thus this pipe is exposed to a lower pressure than is the oil collector discharge pipe 27. An additional evaporator 30 is included in the collector discharge pipe 27 together with a regulating valve 31 and a non-return valve 32.

Normally oil passes through the pipe 27 and the evaporator 30, but when all the oil from the evaporator has passed into the compressor, refrigerating medium passes through the evaporator 30 on the surface of which ice therefore collects. This evaporator 30 therefore serves as an indication that there is no longer any oil in the evaporator and the regulating valve 31 can thus be closed or alternatively adjusted so as to regulate the flow of oil through the pipe 27 in accordance with the rate at which oil collects in the collector 26.

The valve 29 is of the non-return type in order that, in addition to producing a drop in pressure, it may also prevent the refrigerating medium or oil from returning to the evaporator when the compressor is stopped. The non-return valve 32 in the pipe 27 is provided for the same purpose. If desired the spring of the valve 29 may be adjustable so that the difference between the pressures to which the pipes 8 and 27 are exposed may be adjusted.

In the arrangement as shown in Figure 1, the oil collector 26 thus forms a liquid separator arranged on the outlet side of and above the evaporator to which excess of refrigerating liquid is supplied from the evaporator in addition to vapor. This excess which evaporates in the separator carries any oil which gets into the evaporator 4 into the oil collector or separator 26, where, owing to its weight, it sinks to the bottom and is thereupon drawn through the pipe 27 connected to the bottom of the separator into the compressor 1.

In the arrangement shown in Figure 3, the oil collector is inserted in the pipe 7 on the inlet side of and below the evaporator 4 so that oil carried by the refrigerating medium through the condenser and throttling member is deposited in the collector 26 before passing into the evaporator. The oil is thus carried back to the compressor through the pipe 27 without passing through the evaporator 4.

In this arrangement the pipe 27 instead of being connected to the main suction chamber 28 of the compressor, is connected to a subsidiary suction chamber 33 which is formed by reducing the vapor inlet opening 34 in the liner 16 so that there is at least one blade pitch between the end of the opening 34 and the inlet to pipe 27. The valve 29 can in this arrangement be arranged so that it does not produce a fall of pressure between the

suction chamber of the compressor and the pipe 8.

Thus, while in the arrangement shown in Figure 1 the difference of pressure between the pipes 8 and 27 is produced by the load on the valve 29, that is to say, the suction action on pipe 31 is determined and limited while the volume drawn from the evaporator 30 is more independent in the arrangement shown in Figure 3 these conditions are reversed; that is the volume drawn from the additional evaporator 30 is limited whilst the difference of pressure between the two suction pipes 8 and 27 is not limited.

15 The compressor can therefore always draw from the additional evaporator as required by the condition and arrangement of the machine (e. g. the location of the main evaporator) although not more than a given total 20 volume can be drawn into the compressor. The danger of liquid hammering or of wet working is thus less in the construction shown in Figure 3 than in that shown in Figure 1. The suction pressure (always a little less than 25 the pressure in the evaporator 4) will be such that sufficient refrigerating medium in liquid state, with any oil it may contain, will be drawn up to produce, when evaporated, the correct volume for filling the blade spaces 30 passing in front of the opening with gas at the correct pressure.

The additional evaporator through which the direction of flow is from the top to the bottom, in order to ensure that the oil will 35 pass through it and not remain therein as in the main evaporator, may be so dimensioned that it is not necessary to flood the evaporator down to the bottom in order to produce the necessary quantity of gas. Dry gas 40 will therefore be drawn from the additional evaporator in spite of the fact that it is fed from the top.

In the arrangement shown in Figure 4 the main oil separator 9 is connected by an overflow pipe 35 directly to the pipe 6 leading from the condenser 2 to the throttling member 3.

Through this pipe 35 an excess of oil is 50 constantly supplied to the collector 26 so that the oil level in the separator 9 is maintained constant and the condenser 2 being by-passed the excess of oil always keeps the oil level in the collector 26 at such a height above the inlet opening of the discharge pipe 27 of the 55 collector that only pure oil and no refrigerating medium passes from the collector 26 to the compressor. In this way there is no likelihood of the compressor working "wet" and the constant supply of oil to the compressor 60 through the pipe 27 improves materially the lubrication of the working parts and the reduction of leakage losses.

Furthermore in this arrangement the collector 26 may be of a size such that it will 65 hold a large quantity of oil so that in the

event of any oil losses, as for example through the sealing disc 24, the machine will not be directly affected by such leakage. As during normal working no refrigerating medium passes through the pipe 27, an additional evaporator such as 30 (Figure 3) need not be provided in this pipe as no evaporation is likely to take place therein. If, however, this pipe becomes covered with ice it will serve as an indication that the machine is short of oil and therefore further oil must be added.

In the arrangement shown in Figure 5, the refrigerating medium passes through the evaporator 4 in the downward direction so that the oil collector 26 arranged on the outlet side of the evaporator and below it acts not only as an oil separator, but also as a liquid separator in which the excess of liquid refrigerating medium given off by the evaporator collects above the oil and is evaporated by absorbing heat from its surroundings and is then drawn in with the other vapor through the pipe 8 by the compressor.

It will be appreciated that the above description is by way of example only and that many modifications may be made within the scope of the invention. Thus any of the above described constructions can be combined, for example so that the refrigerating medium flows through an evaporator coil in the downward direction, an oil collector provided with an oil discharge pipe, a second evaporator coil in the upward direction, and another oil collector provided with an oil discharge pipe and connected if required on the outlet side of the second evaporator coil.

I claim:

1. In a refrigerating machine the combination of a compressor, an evaporator, an oil collector, a pipe connecting the evaporator to the oil collector, a refrigerant pipe connecting the evaporator to the suction chamber of the compressor, a discharge pipe connecting the oil collector to the compressor, and means for causing a lower pressure in the discharge pipe than the pressure in the refrigerant pipe.

2. In a refrigerating machine the combination of a compressor, an evaporator, an oil collector, a pipe connecting the evaporator to the oil collector, a refrigerant pipe connecting the evaporator to the suction chamber of the compressor, a discharge pipe connecting the oil collector to the compressor, and means for causing a difference between the pressure in the refrigerant pipe and the pressure in the discharge pipe.

3. In a refrigerating machine the combination of a compressor, an evaporator, an oil collector, a pipe connecting the evaporator to the oil collector, a refrigerant pipe connecting the evaporator to the suction chamber of the compressor, a discharge pipe connecting the oil collector to the compressor, means for

causing oil to flow from the oil collector to the compressor, and a non-return valve in the discharge pipe for preventing a reverse flow of the oil.

- 5 4. In a refrigerating machine the combination of a compressor, an evaporator, an oil collector, a pipe connecting the evaporator to the oil collector, a refrigerant pipe connecting the evaporator to the suction chamber of the compressor, a discharge pipe connecting the oil collector to the compressor, and a subsidiary evaporator interposed within the discharge pipe.
- 10 5. In a refrigerating machine the combination of a compressor, an evaporator, an oil collector, a pipe connecting the evaporator to the oil collector, a refrigerant pipe connecting the evaporator to the suction chamber of the compressor, a discharge pipe connecting the oil collector to the compressor, and a subsidiary evaporator interposed within the discharge pipe, said subsidiary evaporator so arranged that the oil flow therein is in a downward direction.
- 15 20 25 In testimony whereof I have affixed my signature.

EMIL KÄGI.
